WRAPPING MACHINE

Charles P. Dyken, Saukville, Wis.

Application May 2, 1950, Serial No. 159,464

4 Claims. (Cl. 242—55)

1

My invention relates to wrapping machines and more particularly to a type of machine that will place an outside sheet or wrapper around a quantity of bound pamphlets, magazines, newspapers, or similar articles.

An object of my invention is to provide a device that will hold a stack of sheets or the like, in engagement with one another and in stacked relation to one another while the wrapping operation is progressing.

Another object of my invention is to provide a device that will adjust itself to any height of stack, or any number of sheets.

Still another object of my invention is to provide a device that is operated by a single actuating means.

When preparing a quantity of newspapers, magazines or the like for mailing, it is necessary to wrap varied quantities, depending on the required number of copies in each bundle being wrapped. With the device specified, claimed and illustrated herein, it is only necessary to place the single sheet of wrapping paper or binder on the bottom conveyer, together with the desired quantity of periodicals and newspapers disposed thereon and they will be conveyed towards the rolls and held in position while they are being put into a compact, tightly-rolled, wrapped package.

The device is simple in construction, easy to operate, and highly efficient for the purpose for which it is intended.

Other and further objects of my invention will become more apparent as the description proceeds when taken in conjunction with the drawing in which:

Figure 1 is a side elevation of the assembled device showing the component parts constituting the device.

Figure 2 is a fragmentary view of the conveyer arrangement, showing a stack of papers on the loading end of the bottom conveyer.

Figure 3 is a similar view showing the papers rolled into a compact package and showing another stack in phantom placed on the conveyer ready for wrapping.

Figure 4 is a top view of the conveyer belt together with the flanged roller at the end of the bottom conveyer, taken at the line 4—4 in Figure 3, and

Figure 5 is a top view of the top roller on the right in Figure 1.

Similar characters of reference indicate corresponding parts throughout the several views, and referring now to the same, the characters 10, 10' 55

2

and 10'' portray a frame construction which may consist of castings or may be as shown constructed of angle iron or structural steel. The frame 10 has vertical end members 11 extending upward therefrom, and also vertical plates shown as 11 and 11' having angularly disposed slots 13 therein. The vertical end members 11 and the vertical plates 12, are provided with bearings 14 and 14' near their upper ends which support shafts 15 and 15' respectively, on which pulleys 16 are rotatably mounted. These pulleys 16 have grooves on their outer periphery for the engagement of cables 17 and 17' which support weights 18 on their free ends.

There is a main conveyer unit consisting of a plurality of V-belts 19 which are horizontally disposed over V-pulleys 20 and 20' spaced apart from one another and mounted on shafts 21 and 21' respectively. These shafts are journaled in bearings 22 and 22' respectively supported by the frame member 10'.

There is an idler roller 23 contacting the lower face of the V-belts 19. This idler roller is journaled on the upper end of pivoted levers 24 mounted on a shaft 25 which is journaled in bearings 26 supported on a portion of the frame 10. The lower depending ends of the levers 24 are provided with springs 27 which are attached at 28 to the base of the frame 10'.

There is an auxiliary conveyer unit consisting of a plurality of V-belts 29 supported by V-belt pulleys 30, 31 and 32 which are mounted on shafts 33, 34 and 35 respectively and spaced apart from one another. All of these shafts are journaled within an auxiliary frame member shown as 36.

The shafts 34 and 35 engage the slots 13 in the vertical plates 12 and 12' and have the other ends of the cables 17 and 17' respectively attached thereto. Obviously, the weights 18 are heavy enough to almost counterbalance the weight of the assembled auxiliary conveyer unit thereby permitting its up and down movement with ease, when guided by the slots 13. The shafts 15 and 15' are equipped with additional pulleys 37 supporting a cable 38 over a portion of their outer peripheral surfaces. This cable 38 equalizes and controls evenly, the revolving of the pulleys 16 supporting the cables 17 and 17'.

The pulleys 30 are of smaller diameter than the pulleys 31, thereby creating an angular section 39 on the bottom of the V-belts 29 to permit the engagement of a stack of periodicals ready to be wrapped as shown at 40 in Figures 2 and 3, between the belts 19 and the belts 29. The height 55 of the stack 40 will determine the height that the

auxiliary conveyer unit will rise when counterbalanced by the weights 18.

The lower surface of the upper V-belt 19 is supported by a roller 41 mounted on a shaft 42, journalled in bearings 43 supported by the angle irons 10' constituting a portion of the frame 10. A motor 44 acting as an actuator for the pulley 45 mounted on the shaft 46 journalled in bearings 47 shown supported by the frame member 10'' revolves the pulley 45 by means of the belt 48. Other bearings 49 are mounted on the frame member 10 and support a shaft 50 on which pulleys 51 and bracket links 52 are mounted, the pulleys 51 being rotated by means of the belt 53 when the pulleys 54 on the shaft 46 are revolved. There are also shown drive belts 55 which revolve the shaft 21 to actuate the conveyer belt 19 on the pulleys 20 and 20'.

The links 52 supported by the shaft 50 also support a shaft 56 at their upper end, and pulleys 57 are mounted thereon and revolved by means of a belt 58 over the pulleys 51. Another set of link members 59 supported by the shaft 56 act as a support for pulleys 60 which are mounted on the shaft 61 which is supported on the frame 36 to revolve the top roller 62 in the wrapping operation. The roller 62 consists of a plurality of discs spaced apart from one another and is free to move up and down with the auxiliary conveyer supported within the frame structure 36.

The shaft 46 also supports a frame 63 which acts as a support for the roller 64 journalled on the shaft 65 and revolved by means of the belt 66 over the pulleys 54 and 67 respectively. The frame 63 is supported at 68 by a piston rod 69 forming a part of a piston and cylinder assembly 70 which is provided with a resilient member 71. The cylinder 70 is hingedly attached at 72 and is actuated by a source of pneumatic pressure (not shown) through the tubular member 73.

In operation, the device functions as follows: The magazines or papers to be wrapped are placed on a piece of wrapping paper disposed onto the top surface of the belts 19 and as the belts 19 travel in the direction as indicated by the arrows in Figure 3, the papers will be conveyed towards the angular portion 39 of the auxiliary conveyer, which belts also travel in the same direction, and as the newspapers or magazines are carried between the belts 19 and 29 towards the rollers 62 and 64, they will be caused to assume a cylindrical contour as shown at 74 in Figure 3, and as the wrapping paper forming the outer wrapper for the rolled articles is provided with a strip of glue at its open end, the revolving of the rollers 62 and 64 together with the pulleys 32 on which the belts 29 are disposed will cause the entire unit to assume a cylindrical contour, and when the pneumatic arrangement of the assembly 70 is put into operation, the piston will be drawn down into the cylinder causing the roller 64 to move downward in its path thereby releasing the rolled periodicals such as the papers or magazines shown at 74.

In the chosen embodiments of my invention, there are many features that are heretofore disclosed in the prior art, and although I have shown a specific arrangement of the component parts constituting the device, I am fully cognizant of the fact that these parts may vary in form and contour and even in arrangement to some extent, without departing from the spirit of my invention or the scope of the appended claims.

Having thus described my invention, what I claim and desire to secure by Letters Patent in the United States is:

1. A wrapping device of the character described incorporating the use of a sheet type of wrapper, said device comprising a main conveyer, an auxiliary conveyer, means for counter-balancing said auxiliary conveyer to permit free vertical separation of said main and auxiliary conveyer one from the other, both of said conveyers comprising belts disposed in parallel relation to one another, the forward portion of said auxiliary conveyer angularly disposed in a manner to raise the forward end of the lower surface of said auxiliary conveyer above the upper surface of said main conveyer, a roller hingedly supported at the rearward end of said auxiliary conveyer and permitted to be raised and lowered with said auxiliary conveyer, a roller at the end of said main conveyer, means for raising and lowering the roller at the end of said main conveyer, both of said rollers being of a diameter greater than the diameter of said conveyers and an actuating means for rotating all of said rollers and said conveyers.

2. A wrapping device comprising a frame, two belt conveyers, one of said conveyers supported by said frame in a stationary manner, the other of said conveyers slidably supported on said frame, both of said conveyers disposed in parallel relation to one another, one above the other, and arranged to travel at equal speed and in the same direction at their contact faces, a pair of rollers, one of said rollers supported at the discharge end of said slidably supported conveyer, the other roller pivotally mounted on said frame at the discharge end of said stationary mounted conveyer, actuating means for actuating all of said conveyers and rollers, and means for pivotally raising and lowering the roller on the discharge end of said stationary mounted conveyer.

3. A wrapping device of the character described comprising in combination, a main frame, a lower conveyer mounted on said frame, an upper conveyer unit, said upper conveyer supported by an auxiliary frame, said auxiliary frame slidably mounted within said main frame, both of said conveyers disposed in parallel relation to one another, a counter-balance attached to said main frame for raising and lowering said auxiliary frame, said main conveyer extending outward at the forward and rearward end of said auxiliary conveyer, both of said conveyers consisting of belts disposed over the outer peripheral surface of pulleys mounted on shafts journalled within bearings mounted on said main and auxiliary frame, a roller mounted to the rearward end of said auxiliary frame and extending outward therefrom, a second roller pivotally mounted to said main frame and extending rearward from said main conveyer, means for raising and lowering said second roller, and actuating means for actuating all of said rollers and conveyers when said actuating means is put into motion.

4. A wrapping machine of the character described comprising a base, a main conveyer horizontally mounted onto said base, said main conveyer consisting of a plurality of belts disposed over a plurality of pulleys mounted on shafts rotatably supported by said base, an auxiliary conveyer unit, said unit comprising a plurality of belts shorter than the belts in said main conveyer, said belts disposed over a plurality of pulleys mounted on shafts supported by an auxiliary conveyer frame, said frame slidably mounted within said base, said belts in said auxiliary conveyer horizontally disposed in parallel relation

to the belts in said main conveyer, the forward pulleys supporting the belts on said auxiliary conveyer being of a smaller diameter than the other pulleys supporting said belts, a counter-balancing means arranged within said base for permitting the raising and lowering of said auxiliary conveyer unit away from and towards said main conveyer, a top roller, said roller consisting of a plurality of vertical discs, said discs mounted on a shaft journaled in the rearward end of said auxiliary conveyer, said discs extending inward between the pulleys constituting the rearward support for the belts of said auxiliary conveyer, a similar bottom roller pivotally mounted to said base, said bottom roller having its vertical discs extending inward between the pulleys constituting said main conveyer, the top roller being raised and lowered with the move-

ment of said auxiliary conveyer unit, means for raising and lowering said bottom roller, and actuating means for operating both of said conveyers and both rollers when said actuating means is set into motion.

CHARLES P. DYKEN.
